1

This invention relates to a machine for operating on footwear, the machine being provided with a work support which moves the shoe being operated on with respect to the tool and consists in this, that the tool support is made to be movable in such a manner as to permit of a partial displacement of the point of application with respect to the work support.

Machines for operating on footwear are already known, in which the clamping device for the shoe, that is the work support, imparts to the shoe to be operated on plane motions which are, for instance, derived from cam discs. These motions are in each case dependent on the shape of the cam discs and are limited as regards the range of motion. In the machines of this type, hitherto known, the supports of the tool or tools were so arranged that the tool could be moved only towards and away from the work, so that the point of application at the work could be varied only by the movement of the work support itself. Moreover, the start and finish of the operation on the work, for instance along the sole edge of a shoe, was thus in each case determined only by the movement of the work support, being thus dependent on the shape of the particular cam disc. Owing to the great diversity in the shapes and sizes of shoes, it was, consequently, necessary to provide for each machine a great number of cam discs, each change of which entailed a considerable loss of time. Furthermore, owing to the inadequate adjustability of the tool support itself, it was not possible always to obtain uniform products, even when operating on shoes of the same form and size, as, in view of the unavoidable differences of the work pieces or inaccurate clamping of the same, the result of the operation does not always turn out alike. The sole edge operated on will then, for instance, show imperfectly finished places which would subsequently have to be put right by hand or in another machine adapted for that purpose. Should the tool be driven too far in the peripheral direction of the sole edge, then, with the usual rigid arrangement of the tool support in this direction, damage to the shoe heel will often occur.

Machines are also known, in which only the forward part of the sole periphery is operated on, whilst the shank parts as far as the heel are operated on by hand. Whilst in such machines it is not a matter of such importance to keep exactly to the starting and finishing position of the tool, when operating on the sole edge, finishing by

2

hand or on other machines becomes unavoidable.

According to the present invention the disadvantages of the machines of the aforesaid type hitherto in use are overcome in a surprisingly simple manner by the expedient that the tool support is made not only movable in the direction towards and away from the work, but also adjustable in the peripheral direction of the work, for example, when operating on the sole edge of a shoe, tangentially to the sole edge. The effect of this is that at the commencement of the operation, the tool can be applied by the operative exactly at the heel and similarly, at the end of the operation, can be taken up to the heel again on the other side, independently of the motion of the work itself, which is positively controlled in a known manner by special cam discs. As a particular advantage of the arrangement according to the invention may be mentioned the possibility of greatly reducing the requisite number of cam discs for different forms and sizes of shoes, as one set of these discs can be made use of for a whole series of different kinds and sizes of shoes. This results in considerable economies in servicing and maintenance costs of the machines of this kind. Finally, a particularly great advantage of the arrangement according to the invention has proved to be the circumstance, that with each shoe the entire sole edge, including the shank parts, can be operated on uninterruptedly and smoothly right up to the heel of the shoe in a completely satisfactory manner.

In order to make the invention more readily understood a description shall now be given with reference to the accompanying drawings of a cut polishing machine, although the practical embodiment of the invention is not limited to these machines, but can also be applied to other similar machines for other operational purposes.

The individual illustrations show:

Figure 1 a side elevation of the machine;

Figure 2 the arrangement of the tool support with the driving mechanism in section and to an enlarged scale;

Figure 3 a view of the tool support in the direction of the arrow III in Figure 1, to an enlarged scale;

Figure 4 a section on line IV—IV of Figure 1 and

Figure 5 a view of the work fixing mechanism seen in the direction of the arrow V in Figure 1.

Figure 6 the tool driving mechanism in section on an enlarged scale.

Figure 7 a detail of Figure 6 also on an enlarged scale.

The fixing means for the shoe consist of a horseshoe-shaped frame 1 which is guided by means of sliding piece 2 in guides of a rotatable head piece 3. The effect of the combination of the rotary and sliding motion is that the sole edge, for instance, travels along past the fixed tool, being operated on during its progress.

The rotary motion of the clamping frame 1 is derived, from cam discs 4, on which bears a roller 5 supported in a fork 6. The fork 6 actuates an arm 7 mounted so as to be capable of rocking on a shaft 10 and provided with a toothed segment 8 which meshes with a toothed pinion 9 which is rigidly coupled with the clamping head 3. The roller 5 is kept in contact with one of the cam discs 4 by means of an air pressure device, see Figure 4, in which a similar device for the control device, described below, of the sliding motion of the clamping frame 1 is illustrated.

The sliding motion of the clamping frame 1 is derived from cam discs 16, against which a roller 17 bears, which is supported in the fork 18 of an arm 19 capable of rocking about the shaft 10. The toothed segment 20 of this lever arm meshes with a pinion 21 on the shaft 22 which is rotatable in the interior of the rotary head 3. The roller 17 is pressed against the periphery of the cam disc by means of a pneumatic cylinder 23 (Figure 4), the piston 24 of which is connected through a piston rod 26 with the arm 25 of the lever 19. The air pressure in the cylinder 23 thus ensures the maintenance of a constant pressure which is independent of the throw of the levers. The oscillation of the pinion 21, taking place in this way, on the cam discs 16 turning, produces a displacement of the clamping frame 1 in the guide ways of the rotary head 3, namely through the rotary motions of the shaft 22 being converted into sliding motions through the intermediary of a suitable device. This device consists of a sprocket wheel 27 (Figure 5) with two chains 28 and 29. The chain 28 is attached with one end to the sprocket wheel 27, say at the point 27', and is taken over a tightening roller 30 which is rotatably supported in the rotary head 3. The other end of the chain 28 is then connected at the point 31 with the sliding part of the clamping frame 1. The other chain 29 is attached alongside the chain 28 to the sprocket wheel 27, also at about the point 27', and, after passing about once round the wheel, is taken over an oppositely disposed tightening roller 32, being connected at its other end with the sliding part at the point 33. The sliding motions of the clamping frame 1 are in this way accurately limited and are determined by the size and shape of the cam disc which happens to be in position. When changing over from one cam disc to another, the roller 17 (and also the roller 16 of the previously described arrangement) is temporarily lifted from the cam disc by reversing the compressed air in the appropriate cylinder 23.

The drive of the cam discs 4 and 16 is provided by a motor 35 (Figure 1) by means of a belt drive over gear wheels 38, 39 and worm gearing 40, 41 to the shaft 42. The motor is supplied with electric current from a power line 109. On this shaft 42 is keyed, besides the cam discs 4 and 16, a cam disc 43 which controls a device for fixing the tool support in a definite position, which device also constitutes releasing means

permitting the tool to be moved by hand in certain phases of operation of the machine. For this purpose the roller 44 of the fork 45 of a pressure-transmitting bar 46 is actuated by the cam disc 43 which, according to its shape, brings about at definite moments in conjunction with the cam discs 4 and 16, that is, as soon as these discs initiate or terminate the operative motions of the clamping frame 1, a displacement of the pressure transmitting bar 46 in the guide 47 and thereby pushes the end 48 of the bar 46 into or out of the recess 49 of a bracket 50 (Figures 1 and 4). This bracket 50 is rotatable about a vertical pivot 52 (Figure 2) and carries four two-armed levers 51 and 51' which are suspended so as to be rotatable about pivots 53, 53' perpendicular to the axis of rotation 52 of the bracket 50. The result of this arrangement is that after the release of the bracket 50 through the bar end 48 being pushed out of the recess 49, the unsupported ends of the levers 51, 51' can be displaced both about the pivot 52 and the perpendicular pivots 53, 53.

Now, the four parallel levers 51, 51' support at one end a driving device (Figure 1) for the derivation of the operative movement of the tool with an accessory tool support 55 and at the other end the driving motor 56 which at the same time serves the purpose of a counterpoise. The motor 56 is supplied with electric current by the conductor 110. The drive from the motor 56 to the belt pulley 57 is by way of a belt 58 (Figure 2) which is made of elastic material and is capable of adapting itself during the working operation to the variations in the axial distance between the belt pulley 59 of the motor and the belt pulley 57.

The tool is pressed against the working surface, that is to say, against the periphery of the sole, with constant pressure which is produced by a pneumatic cylinder 60 (Figure 2) through the intermediary of the piston 61 which acts on a screw 62. The screw 62 is adjustable in a projecting part 63 of the bracket 50. The pneumatic cylinder 60 is fixed to one of the levers 51'. At the end of the operation the tool is lifted automatically from the work, this being effected through the action of the tension spring 64 attached to the bracket 50 and through the weight 50 of the motor 56, as soon as the pressure in the cylinder 60 ceases to be effective.

The device for the derivation of operative movements of the tool which, in the case of a cut polishing machine, performs oscillatory motions is known per se and shall be described below only as far as appears necessary for explaining the invention. The form of a device which also effects the adjustment of the tool mentioned later, appears from Figs. 2 and 6. The pulley 57 is keyed upon a shaft 97 which is journaled in bearings 98, 98' of box 66, 66'. The middle portion 99 (see also Fig. 7) of shaft 97 between bearings 98, 98' is angularly offset to the axis of the shaft angle and carries two bearings 101 within sleeve 100. This sleeve is provided with two trunnions 102 the longitudinal axis of which passes through the point of intersection of the axis of bearings 98, 98' and of the axis of the angularly related axis of portion 99. The trunnions 102 carry a bail 103 which on one side is integral with the box 104 rotatably mounted in bearings 105, 107 and on the other side is provided with a trunnion 106 which is journaled in bearing 105' between the housing halves 66, 66'. Since the housing halves 66, 66'

are journaled in the bearing 108 of box 18 and exteriorly of this box are provided with a pinion 71, the housing halves 66, 66' together with the mechanism housed in box 18 are rotatable in bearings 107, 108. Box 104 carries a rigidly held pin 65 with ball 72.

The operation of this device is as follows: During rotation of pulley 57 driven by motor 56, During rotation of pulley 57 driven by motor 56, the shaft 97 turns together with the angularly offset portion 99 which in consequence of its oblique position by the intermediary of sleeve 100 and trunnion 102 causes an oscillation of bail 103 in the bearings 105, 105'. This oscillation of bail 103 is by the intermediary of box 104 of trunnion 65 transmitted to ball 72 and from the latter over lugs 13, 13' to the toothed wheel 76 (Fig. 3). This wheel 76 meshes with racks 85, 85' from which the to and fro movements are transmitted to the tool 80. Since the obliquity of portion 99 of shaft 97 is comparatively small, the oscillation of bail 103 and the entire drive assembly of the tool coordinated therewith is also small, but has a comparatively high frequency.

An eventual turning of the driving device is effected for the purpose of changing the operative surface of the tool, during the operation at the moment where the forward part of the sole edge merges into the shank part. Such a turning is brought about through the action of compressed air on the piston 68 of a cylinder 69 and the turning produced thereby of the pinion 71 by the toothed 70 of the piston 68. The pinion 71 which embraces the two casing halves 66, 66' causes the whole inner gear box to turn. As long as shoes are being operated on, which require no change of the tool surfaces, the gear box 66, 66' is secured against turning by a screw 67.

The ball 72 of the pivot 65 carries two lugs 13, 13' which lie in internal keyways 14, 15 of the toothed wheel 76 (Figure 3) and permit the tool support to oscillate in a plane perpendicular to the axis of the gudgeons 71, 71' even during the operation. Such an oscillatory movement takes place for the purpose of following the sole edge by turning the tool support about the horizontal gudgeon pins 71, 71' which are fixed to supporting arms 79, 79' of the outer gear box 18 (Figure 2). For enabling this oscillatory movement of the tool support to take place and the toothed wheel 76 to be placed on the ball 72, the wheel has a corresponding spherical cavity.

The transmission of the rotary oscillations of the pivot pin 65 or the toothed wheel 76, already referred to, to the actual tool 80 which is rotatable about the pin 81 (Figure 3) is effected through the intermediary of a toothed wheel 84 by way of toothed segments 82, 83 and the racks 85, 85'. These racks are kept in mesh with the respective toothed wheels by pins 86 supported by adjustable holders 81, 81', which pins may be provided with guide rollers. The actual tool support 88 is in addition suspended in a bearing 90 of a transverse member 95, so as to be capable of rotary motion, and thus makes also possible an adaptation to any angular deviations in following the periphery of the sole. The oscillatory movements of the tool support 88 are also taken part in by the guiding parts 81, 81' fixed to it and also by the racks 85, 85' as well as the toothed wheel 76, which movements, however, the ball 72 readily permits within certain limits.

In Figure 2 two tools 80, 80' are arranged next to one another, which are intended for alternately operating on a right or left shoe. Each of these tools is so mounted as to be capable of

rocking on knife edges 92, 92' for enabling it to be perfectly adapted to the surface of the sole edge to be operated on. The necessary displacement for the purpose of the adjustment, according to whether a right shoe or a left shoe is to be operated on, is effected by means of a pneumatic cylinder 93 (Figure 2) which, after actuating an appropriate valve, produces the required displacement along the pins 91, 91'. The heating of the tools, required in polishing machines, is effected by an electric heating body 94.

For guiding the tools by hand there is provided a handle 96 which, in the arrangement according to the invention, enables the tool to be applied in its initial position against the sole edge close to the heel, the rotatable bracket 50 not yet being blocked, and also enables the tool to be guided by hand or permits an adjustment of the operative point with respect to the still stationary work up to the moment when the cam discs 4, 16 and 43 begin to act. Similarly, after the cam discs 4, 16 have ceased to act and the bracket 50 has been released by disengagement of the end 48 of the bar 46 from the recess 49, the arrangement according to the invention enables the tool to be moved again, over a portion of the sole edge already operated on, by hand close up to the heel. This provides the possibility of advantage for certain operative phases of getting away from the automatic, constrained motion of the tool.

I claim:

1. A machine for operating on footwear comprising a work support for holding the shoe to be operated on, a tool for operating on the shoe, a tool support carrying the said tool and movable in two directions, means for moving the work support so as to move the shoe in relation to the tool, releasable means for holding the tool support against movement in one of said directions, and means effective in a predetermined position of the work support for releasing said holding means, the tool support being movable, when released, in such a manner as to permit of a partial displacement of the point of application of the tool to the shoe in the direction of the sole edge being operated upon.

2. A machine for operating on footwear comprising a work support for holding the shoe to be operated on, a tool for operating on the shoe, means for moving the work support so as to move the shoe in relation to the tool, means for transmitting operative motions to the tool, a tool support carrying the said tool and also carrying the said transmitting means, the said tool support being rotatable about two axes, one of which is perpendicular to the plane tangent to the sole surface being operated upon, the other being approximately perpendicular to the first said axis and at the same time being parallel to the said plane, releasable means for holding the tool support against movement about one of said axes, and means effective in a predetermined position of the work support for releasing said holding means, the said tool support being movable, when released, in such a manner as to permit of a partial displacement of the point of application of the tool to the shoe in the direction of the sole edge being operated upon.

3. A machine for operating on footwear comprising a work support for holding the shoe to be operated on, a tool for operating on the shoe, means for transmitting operative motions to the tool, a tool support carrying the said tool and also carrying the said transmitting means, four

two-armed parallel levers turning about a common axis, the tool support being suspended in the said levers, a driving electric motor carried by the said levers at one end thereof, the motion-transmitting means being carried by the said levers at the other end thereof, the tool support being movable in such a manner as to permit of a partial displacement of the point of application of the tool to the shoe in relation to the work support and means for moving the work support so as to move the shoe in relation to the tool.

4. A machine for operating on footwear comprising a work support for holding the shoe to be operated on, a tool for operating on the shoe, means for transmitting operative motions to the tool, a tool support carrying the said tool and also carrying the said transmitting means, four two-armed parallel levers turning about a common axis, the tool support being suspended in the said levers, a driving electric motor carried by the said levers at one end thereof, the motion-transmitting means being carried by the said levers at the other end thereof, the tool support being movable in such a manner as to permit of a partial displacement of the point of application of the tool to the shoe in relation to the work support, means for moving the work support so as to move the shoe in relation to the tool, and a ball pivot carried by the parallel levers, a portion of the motion-transmitting means being suspended from the ball pivot through which the drive is transmitted, thereby enabling the position of the tool to be adapted to various inequalities in the curvature of the surface of the work on which it operates.

5. A machine for operating on footwear comprising a work support for holding the shoe to be operated on, a tool for operating on the shoe, means for transmitting operative motions to the tool, a tool support carrying the said tool and also carrying the said transmitting means, the said tool support being rotatable about two axes perpendicular to one another and being movable in

such a manner as to permit of a partial displacement of the point of application of the tool to the shoe in relation to the work support, means for moving the work support so as to move the shoe in relation to the tool, a ball pivot carried by the tool support and constituting an element of the motion-transmitting means, a portion of the motion-transmitting means being suspended from the ball pivot, means for imparting an oscillatory rotary motion to the ball pivot about its own axis, and racks for transmitting this oscillatory rotary motion to the tool.

6. A machine for operating on footwear, comprising a work support for holding the shoe to be operated on, a tool for operating on the shoe, means for transmitting operative motions to the tool, a tool support carrying the said tool and also carrying the said transmitting means, the said tool support being rotatable about two axes perpendicular to one another and being movable in such a manner as to permit of a partial displacement of the point of application of the tool to the shoe in relation to the work support, means for moving the work support so as to move the shoe in relation to the tool, a ball pivot carried by the tool support and constituting an element of the motion-transmitting means, a portion of the motion-transmitting means being suspended from the ball pivot, means for imparting an oscillatory rotary motion to the ball pivot about its own axis, racks for transmitting this oscillatory rotary motion to the tool, and adjusting means connected with the ball pivot to enable the working surface of the tool to be displaced while the machine is in operation.
